US00D688910S

(12) **United States Design Patent**
Montgomery

(10) **Patent No.:** **US D688,910 S**
(45) **Date of Patent:** **** Sep. 3, 2013**

(54) **PAN WITH A UTENSIL RETENTION
FEATURE**

(75) Inventor: **Seana L. Montgomery**, McKinney, TX
(US)

(73) Assignee: **Seana L. Montgomery**, McKinney, TX
(US)

(**) Term: **14 Years**

(21) Appl. No.: **29/428,261**

(22) Filed: **Jul. 27, 2012**

Related U.S. Application Data

(62) Division of application No. 29/369,663, filed on Sep. 10, 2010, now Pat. No. Des. 666,458.

(51) **LOC (9) Cl.** **07-02**

CLAIM

The ornamental design for a pan with a utensil retention feature, as shown and described.

DESCRIPTION

This Design Application is also related to co-pending U.S. Design patent application Ser. No. 29/428,184, filed on Jul. 27, 2012, entitled Bowl With Utensil Retention Feature; U.S. Design patent application Ser. No. 29/428,185, filed on Jul. 27, 2012, entitled Bowl With Utensil Retention Feature; U.S. Design patent application Ser. No. 29/428,187, filed on Jul. 27, 2012, entitled Bowl With Utensil Retention Feature; U.S. Design patent application Ser. No. 29/428,188, filed on Jul. 27, 2012, entitled Bowl With Utensil Retention Feature; U.S. Design patent application Ser. No. 29/428,189, filed on Jul. 27, 2012, entitled Bowl With Utensil Retention Feature; U.S. Design patent application Ser. No. 29/428,211, filed on Jul. 27, 2012, entitled Bowl With Utensil Retention Feature; U.S. Design patent application Ser. No. 29/428,212, filed on Jul. 27, 2012, entitled Bowl With Utensil Retention Feature; U.S. Design patent application Ser. No. 29/428,221, filed on Jul. 27, 2012, entitled Bowl With Utensil Retention Feature; U.S. Design patent application Ser. No. 29/428,222, filed on Jul. 27, 2012, entitled Bowl With Utensil Retention Feature; U.S. Design patent application Ser. No. 29/428,225 filed on Jul. 27, 2012, entitled Bowl With Utensil Retention Feature; U.S. Design patent application Ser. No. 29/428,227, filed on Jul. 27, 2012, entitled Bowl With Utensil Retention Feature; U.S. Design patent application Ser. No. 29/428,232, filed on Jul. 27, 2012, entitled Bowl With Utensil Retention Feature; U.S. Design patent application Ser. No. 29/428,240, filed on Jul. 27, 2012, entitled Bowl With Utensil Retention Feature; U.S. Design patent application Ser. No. 29/428,244, filed on Jul. 27, 2012, entitled Bowl With Utensil Retention Feature; U.S. Design patent application Ser. No. 29/428,248, filed on Jul. 27, 2012, entitled Bowl With Utensil Retention Feature; U.S. Design patent application Ser. No. 29/428,253, filed on Jul. 27, 2012, entitled Bowl With Utensil Retention Feature; U.S. Design patent application Ser. No. 29/428,256, filed on Jul. 27, 2012, entitled Bowl With Utensil Retention Feature; and U.S. Design patent application Ser. No. 29/428,279, filed on Jul. 27, 2012, entitled Bowl With Utensil Retention Feature. The disclosure of these Design Applications are considered part of and are incorporated by reference in the disclosure of this design application.

FIG. 1 is a top perspective view showing a pan with a utensil retention feature;

FIG. 2 is a front view of FIG. 1;

FIG. 3 is a back view of FIG. 1;

FIG. 4 is a side view of FIG. 1;

FIG. 5 is another side view of FIG. 1;

FIG. 6 is a top view of FIG. 1; and,

FIG. 7 is a bottom view of FIG. 1.

The broken lines of the preceding FIGURES are included for the purpose of illustrating environment and form no part of the claimed design.
